HOLDER FOR A TEMPLATE AND A PUNCHABLE CARD

John W. Whitson, 21 Cabrini Blvd., New York, N.Y.

Filed May 25, 1960, Ser. No. 60,729

Term of patent 14 years

(Cl. D74—1)

FIG. 2

FIG. 1 is a side perspective view of a holder for a template and a punchable card showing my new design, the side opposite thereto being similar in appearance; and

FIG. 2 is a rear elevational view thereof.

The essential features of the design reside in the portions shown in solid lines on the drawing.

I claim:

The ornamental design for a holder for a template and a punchable card, as shown and described.
